PACKAGING MACHINE

Michael J. Grebowiec, Kansas City, Kans., assignor to Remington Arms Company, Inc., Bridgeport, Conn., a corporation of Delaware

Application May 15, 1945, Serial No. 593,923

10 Claims. (Cl. 86—47)

1

The present invention relates to packaging machines, and particularly a machine for successively separating a continuous row of inter-engaged articles into groups of a desired number and successively feeding each group into a carton designed to receive the group of articles in their interengaged relation. The machine is especially intended for the packaging of belt links of the type used for ammunition belts, and wherein each link consists of two axially spaced and aligned end bands and an intermediate axially offset band integrally connected to the end bands, this intermediate band of each link adapted to be interengaged in the space between the end bands of the forwardly adjacent link. The interengaged links are hingedly connected by the engagement therewith of the cartridges, each cartridge being engaged with the two end bands of one link and the interengaged intermediate band of the adjacent link.

Upon occasion it becomes necessary to de-link the ammunition belt by removing the cartridges, and this operation is performed in a de-linking machine into which the ammunition belt is fed, the cartridges being successively withdrawn therefrom so that the individual links become loose and free to separate from each other as the cartridges are disengaged therefrom. It is proposed in the present invention to provide a packaging machine into which the interengaged links are continuously fed from the de-linking machine, while still remaining in interengaged relation with each other, to the end that packaging of the links may be carried out without the operation, heretofore required, of manually re-arranging the separated links in interengaged relation, thus effecting a great saving of time in the packaging of the links and protecting them from such damage as is apt to take place under the previous practice of directing the loose links from the de-linking machine into barrels.

A further object is to provide a packaging machine in which the row of interengaged links is adapted to have the desired number of links to be packaged, as for example ten links, separated from interengaged relation with the following links in the row, and thereupon ejected into the carton, and to this end it is proposed to provide ejector feed means arranged to engage the end bands of the last link of the group to be ejected, so that upon ejecting movement thereof these end bands are disengaged from the intermediate link of the succeeding link in the row.

It is further proposed to provide actuating means for effecting the intermittent operation of

2

the ejector feed means adapted to be actuated by the foremost link of the group to be fed, and arranged to be engaged by the forwardly projecting intermediate band of this foremost link under the forward feed pressure of the fully interengaged group of links to be ejected.

5 A further object is to provide a packaging machine in which pressure means is provided for assembling and maintaining the links of each group to be separated and ejected in their fully interengaged relation with each other.

10 A further object is to provide a packaging machine in which the movement of the row of articles therethrough is imparted thereto through the intermittent movement of the adjacent de-linking machine, wherein indexing means is provided to intermittently feed the successive links of the ammunition belt into position to have the cartridges successively removed.

15 20 With the above and other objects in view, an embodiment of the invention is shown in the accompanying drawings, and this embodiment will be hereinafter more fully described with reference thereto, and the invention will be finally 25 pointed out in the claims.

In the drawings:

20 Fig. 1 is a side elevation of the packaging machine according to the illustrated exemplary embodiment of the invention, and showing a portion of the ammunition belt de-linking machine associated therewith.

Fig. 2 is a plan view.

25 Fig. 3 is a longitudinal sectional view, partially broken away and on an enlarged scale, of the packaging machine, taken along the line 3—3 of Fig. 2, the dot-and-dash lines showing the actuated position of the ejector slide control lever.

30 Fig. 4 is a fragmentary side elevation, showing the ejector slide actuating means in the position to which it is moved by operation of the control lever to the dot-and-dash line position shown in Fig. 3.

35 Fig. 5 is a side elevation showing the fully projected position of the ejector slide.

40 Fig. 6 is a fragmentary plan view, showing the ejector slide actuating means in the position to which it is moved by the full projection of the ejector slide, as shown in Fig. 5.

45 Fig. 7 is a transverse vertical sectional view, taken along the line 7—7 of Fig. 3.

50 Fig. 8 is a transverse vertical sectional view, taken along the line 8—8 of Fig. 3.

55 Fig. 9 is a top plan view of the chute member of the machine, partially broken away, and with

the associated parts of the machine normally mounted thereon removed.

Fig. 10 is a bottom plan view of the chute member.

Fig. 11 is a perspective view of one of the pressure spring retaining clips employed in the machine.

Fig. 12 is a perspective view of one of the pressure springs.

Fig. 13 is a perspective view of one of the ammunition belt links of the type illustrated as being packaged in the illustrated exemplary embodiment of the invention.

Similar reference characters indicate corresponding parts throughout the several figures of the drawings.

Referring to the drawings, the packaging machine according to the illustrated exemplary embodiment of the invention, is shown associated with an ammunition belt de-linking machine 10 provided with an indexing gear 11 which intermittently feeds the ammunition belt to successively bring the cartridges 12 into position to be withdrawn from the belt, as indicated by the arrow in Fig. 2, by a suitable extractor mechanism, not shown. The belt is made up of a series of interengaged or meshed link members of the type illustrated in Fig. 13, each consisting of forward and rearward axially aligned and axially spaced end bands 13 and 14, and an axially offset intermediate band 15 integrally connected to the end bands by extended web portions 16 and 17 of the end bands. The forward end band 13 is tapered to receive the reduced diameter neck portion of the cartridge, while the rearward end band 14 and the intermediate band 15 are of substantially cylindrical form to receive the body of the cartridge, and in practice the links are interengaged so that the intermediate band 15 of one link engages between the end bands 13 and 14 of the adjacent link, a cartridge being inserted through the aligned bands 14, 15 and 13 to thereby hingedly connect the links.

Adjacent the indexing gear 11 there is provided a downwardly curved guide plate 18 upon which the links move from the indexing gear through the intermittent indexing movement of the gear following each cartridge extracting operation, an upper guide arm 19 being provided to engage the upper sides of the links to retain them in interengaged relation. According to the invention the interengaged links move from the guide 18 into the feed chute of the packaging machine and are propelled therethrough through the feeding force of the indexing gear.

The packaging machine comprises an elongated horizontally disposed chute member of rectangular cross-section consisting of a top strip 20, a bottom strip 21 and side strips 22-22, the latter being provided upon their inner sides adjacent their upper and lower edges with angular seating recesses 23 in which the side edges of the top and bottom strips are engaged and secured by screws 26. The vertical depth of the recesses 23 is slightly greater than the thickness of the top and bottom strips, so that the outer surfaces of the latter are slightly inset with respect to the upper and lower edge surfaces of the side strips, and which are adapted to provide slideway surfaces for the ejector slide of the machine, as will presently more fully appear. At its forward end the bottom strip projects beyond the forward edge of the top strip to provide a support for the article receiving carton C, as shown by dot-and-dash

lines in Fig. 1, the forward ends of the side strips being provided at their lower edges with forwardly projecting supporting portions 25 to support the forwardly projecting end of the bottom strip.

Carton guides 26-26 are secured upon the forward ends of the side strips 22-22 and project above the forwardly projecting portions 25, their inner faces being inclined to provide a converging entrance for the convenient engagement of the open end of the carton with the end of the chute. The rearward ends of these carton guides provide abutment stops 27-27 upon the outer sides of the chute member to limit the forward ejecting movement of the ejector feed slide, as will presently more fully appear.

At its rearward end the chute has secured to its under side a cross bar 28, which projects outwardly at each side and is secured to the forward end of the curved guide 18 by means of bolts 29-29. At a point intermediate its ends, the chute is supported by means of a vertical support member 30 secured to the chute bottom and provided with a horizontal base 31 bolted to the base 32 of the de-linking machine.

The ejector feed slide is slidably mounted for reciprocating movement upon the chute, and comprises side plates 33-33, provided upon their inner faces with slideway channels 34 having sliding engagement with the sides of the chute member, a top plate 35 secured upon the upper ends of the side plates, and a bottom plate 36 secured upon the lower ends. The forward edge of the bottom plate 36 is rearwardly spaced from the forward ends of the side plates 33, and at the lower corners of the side plates, below the chute member and forwardly of the bottom plate 36, there is pivotally mounted a cross shaft 37 upon which are secured ejector fingers 38 and 39, these fingers projecting at an inclined angle upwardly and forwardly through longitudinal slots 40-40 provided along the side edges of the chute bottom 21. The slots 40 extend from a point contiguous to the forward end of the chute bottom to a point within the ejector feed slide in the retracted position of the latter. Centrally of the cross shaft 37 there is secured a rearwardly projecting finger control arm 41, normally resting upon the upper surface of the bottom plate 36 and engaged by the forward end of a leaf spring 42 secured to the bottom plate by means of bolts 43-43. The angular relation of the control arm 41 to the ejector fingers is such that in the normal article ejecting position, as shown in Figs. 1 and 5, the ejector fingers project into the chute into position to engage behind the end bands 13 and 14 of one of the link members, the yieldability of the leaf spring 42 permitting the ejector fingers to be pressed in counter-clockwise direction, to permit the forward feed of the links over the fingers in the retracted position of the ejector feed slide, and to permit the fingers to ride under the links during the retracting movement of the ejector feed slide.

Projecting movement is imparted to the ejector feed slide by a piston rod 44 connected at its forward end to an angular bracket 45 secured upon the under side of the bottom plate 36 by the bolts 43, the piston head 44a at the rearward end of the rod being engaged in an air cylinder 46 supported upon the chute bottom in brackets 47-47. Retracting movement is imparted to the slide by a pair of helical compression spring 48-48 connected at their forward ends to studs 49 at each

side of the slide and connected at their rearward ends to screws 50 secured upon the projecting ends of the cross bar 28 at the rearward end of the chute member. Longitudinally adjustable stop screws 51—51 are provided at each side of the upper end of the chute support 30 and are engaged by the rearward edges of the side plates 33 of the slide to limit the retracted position of the slide under the pull of the springs 48.

Compressed air is supplied to the air cylinder through an air feed pipe 52 extending from the rearward end of the air cylinder to a control valve 53 secured upon the chute top, the compressed air being supplied to the control valve through an air supply pipe 54, preferably having a shut off cock 55 inserted therein to enable the air supply to be shut off when the machine is inoperative. The control valve is provided with a vertically disposed cylindrical bore 56, to which three radial ports extend, one port 57 being connected to the air supply pipe 54, a second port 58 being connected to the air feed pipe 52, and a third port 59 being the exhaust port and opening to the atmosphere. The port 58 connected to the feed pipe 52 and the exhaust port 59 are in the same horizontal plane, while the port 57 connected to the air supply pipe 54 is in a downwardly offset horizontal plane, for a purpose presently to be more fully described.

Within the bore 56 there is secured a cylindrical bushing 60 provided with circular ports 61 and 62, respectively in register with the ports 57 and 59, and with a vertically elongated port 63 having its upper end in register with the port 58 connected to the air feed pipe 52 and in the horizontal plane of the exhaust port 59, while its lower end is in the horizontal plane of the port 57 connected to the air supply pipe 54.

Slidably engaged within the bushing is a cylindrical valve core 64 provided at its lower end with a flange 65 disposed beneath the lower end of the bushing 60, this lower end of the bushing being upwardly spaced from the base of the bore 56 to provide a space in which the flange 65 moves during the upward and downward sliding movement of the valve core, abutment of the flange with the lower end of the bushing limiting the upward movement, and the abutment of the lower end of the core with the bottom of the bore limiting the downward movement. This movement is predetermined to correspond to the vertical offset distance between the air supply port 57 and the feed and exhaust ports 58 and 59. Intermediate its ends the valve core is provided with an annular groove 66 adapted in the raised position of the core to register with the feed port 58 and the exhaust port 59, and in the lowered position of the core to register with the lower end of the vertically elongated slot 63 and the air supply port 57.

Thus in the raised position of the core, Figs. 3 and 5, the air cylinder 44 is in communication with the atmosphere through the pipe 52, the port 58, the upper end of the slot 63, the groove 66, the port 62 and the exhaust port 59. In the lowered position of the core, Fig. 4, compressed air is supplied to the air cylinder through the air supply pipe 54, the port 51, the port 61, the groove 66, the slot 63, the port 58 and the feed pipe 52, to cause the ejector feed slide to be projected forwardly.

The core 64 is provided with a stepped axial bore 67, in the upper reduced passage of which is engaged a plunger 68 provided at its lower end with a flange 69 normally forced upwardly

against the step of the bore by a helical spring 70 disposed within the lower enlarged passage, this spring being retained by a threaded plug 71 screwed in the lower threaded end of the bore. The valve core is normally retained in its raised position by means of springs 72, connected between studs 73—73 at each side of the upper end of the core and a lift lever 74, the latter being of bell crank form and pivotally mounted by means of a cross pin 75 in a bracket member 76 secured upon the upper side of the valve body.

The downwardly extending arm of the lift lever is engaged at the forward side of a collar 77 secured upon a horizontally disposed valve control rod 78, having sliding bearing at its rearward end in a passage 79 of the bracket 76, and at its forward end in a bracket 80 secured to the forward end of the chute top, a movement limiting collar 82 being secured upon the forward end of the control rod forwardly of the bracket 80. A collar 83 is secured upon the rod 78 in rearwardly spaced relation to the bracket 80, and a helical spring 84 is disposed between the collar 83 and the bracket 80 normally exerting rearward pressure upon the rod 78 to engage the movement limiting collar 82 with the bracket 80. In this retracted position of the rod 78 the springs 72 of the lift lever 74 retain the valve core in its raised position. The resistance of these springs however, is less than that of the plunger spring 70 within the core, so that, upon downward pressure being applied to the end of plunger 68, the springs 72 yield while the spring 70 resists compression, and therefore the core is pressed downwardly by the plunger.

Automatic actuation of the valve to cause the feed slide to be projected is accomplished through cooperation of the valve control means with the foremost link being fed in the chute, and at a point where the chute contains a continuous line of fully interengaged links and the feeding force of the indexing gear 11 transmits sufficient pressure to the foremost link to impart movement to the valve control means. For this purpose there is provided a valve control lever 85 pivotally mounted near its forward end in a bracket 86 secured to the chute top, the forward end of the control lever being provided with a downwardly projecting contact portion 87, disposed in a slot 88 in the forward end of the chute top and normally having its lower surface projecting within the chute in the path of the intermediate bend portion 15 of the foremost link member.

Upon the rearward end of the control lever there is secured an extension bracket member 89 engaged through the passage of the ejector feed slide between the chute top and the top plate 35 of the slide, this bracket member being bent upwardly at the rear of the feed slide and being provided at its upper end with a laterally disposed bearing support portion 90. The bracket member 89 is normally maintained in its raised position by means of a helical spring 91 disposed beneath the rearward arm of the control lever 85 and having its ends engaged in pockets 92 and 93 respectively provided in the lever and the chute top. Upon the under side of the bearing support portion 90 there is pivotally mounted by means of a pivot stud 94 a valve check lever 95 normally projecting directly above the plunger 68 of the air valve, being yieldably held in this position against a stop lug 96 by means of a spring 97 connected between an outwardly projecting arm 98 of the valve check lever and a spring arm 99 secured to

the upper end of the bracket member. The valve check lever is provided with an actuating finger 100 projecting outwardly at the opposite side from the arm 98 and normally disposed slightly forwardly of and in upwardly raised relation to a collar 101 secured to the valve control rod 78, whereby downward valve actuating movement of the bracket member 89 is adapted to dispose the end of the actuating finger 100 forwardly in the path of the collar 101, as will presently more fully appear.

A lever equalizer arm 102 is pivotally mounted at its rearward end upon a bracket 103 secured upon the chute top at one side of the valve control lever 85, and projects forwardly to a point slightly rearwardly of the mounting bracket 86 of the valve control lever, being engaged intermediate its ends with a horizontally projecting pin 104 secured to the valve control lever. The forward end of the equalizer arm normally projects above the valve control lever 85 and in the forwardly projected position of the feed slide is adapted to be engaged thereby to retain the valve control lever in its actuated position, as shown in Fig. 5. Due to the off center location of the pivot of the control lever, and the tolerance between the lever and the ejector slide in its projected positions, the lever equalizer arm functions to maintain the necessary depressed position of the control lever, and consequently, a constant pressure on the valve plunger 68 controlling the valve action.

Upon the upper side of the ejector feed slide there is secured a valve rod actuating bracket 105 having a recess 105a in its upper end engaged by the valve control rod 78. Upon the forward movement of the slide the bracket 105 engages the collar 83 of the control rod to move it forwardly for the purpose of actuating the air control valve to its position to effect retraction of the slide, as will presently more fully appear.

The top strip 21 of the chute member is provided along its rearward portion with a pair of longitudinally aligned slots 106-106 disposed at one side of the longitudinal center line, so that the inner edges of the end bands 14 of the belt links are in line therewith, a pressure leaf spring 107 being secured upon the dividing portion of the top strip between the two slots and projecting downwardly within the forwardly disposed slot to engage the upper surfaces of the end bands 14 and the intermediate bands 15 of the interengaged links, so that as they are fed into the chute under the feeding force of the indexing gear pressure is exerted thereon to cause them to fully interengage with each other.

Along the forward portion of the top strip and directly beneath the valve control lever 85 there are provided two longitudinally aligned pairs of parallel slots 108-108, disposed forwardly and rearwardly of the pocket 93 in which the spring 91 is engaged. The strips between the slots provide longitudinally extending ribs 109-109 upon which are mounted a series of aligning springs 110 arranged to engage the forward group of links in the chute after they pass forwardly of the ejector fingers of the slide to retain these links in fully interengaged or meshed relation. These springs are of hair pin form and are each secured by a clip 111 of inverted U-shape which straddles the rib 109 and is secured thereto by a screw 112, the bight of the spring being engaged about the screw beneath the top of the clip and its side legs extending downwardly at a forward angle at each side of the rib with their lower ends projecting

into the passage-way of the chute, these ends being curved to engage the upper sides of the intermediate band portion 15 of the links with a wiping action as the links are fed forwardly.

A guard plate 113 is secured to the bracket 86, and serves to protect the hands of the operator as the cartons are successively placed at the end of the chute, and also holds the cover flap of the carton in open position.

The operation is as follows:

As shown in Fig. 3 the continuous row of interengaged links has reached a point in the chute member, under the propelling force from the indexing gear 11 of the de-linking machine, where the intermediate band 15 of the foremost link is about to engage and operate the valve control lever 85. Further propelling movement causes the band 15 of the foremost link to engage beneath the contact portion 87 of the valve control lever, as shown by the dot-and-dash lines in Fig. 3, causing the control lever to be moved to its depressed position, as shown in Figs. 4 and 5 and depressing the core 64 of the control valve. In this position of the valve core compressed air flows from the supply pipe 54 through the valve to the feed pipe 52, and thence to the air cylinder 48, causing the piston rod to be projected forwardly to impart forward movement to the ejector feed slide. At the point where the air valve is actuated there are ten fully interengaged link members disposed forwardly of the ejector fingers 38 and 39, which respectively engage behind the end bands 13 and 14 of the tenth link, and as the slide is moved forwardly the group of ten links is ejected into the carton C, the last link of the group being disengaged from the intermediate band 15 of the following link in the chute, as shown in Fig. 5.

During the final portion of the projecting movement of the ejector feed slide into engagement with the limit stops 21, the bracket 105 engages the collar 83 of the valve control rod 78 moving it forwardly to the position shown in Figs. 5 and 6. This causes the collar 101 to engage the actuating finger 100 of the valve check lever 95, swinging it in counter-clockwise direction to disengage the check lever from the upper end of the valve plunger 68. At the same time the collar 77 of the control rod swings the lift lever 74 upwardly, and through the pull of the springs 72 the valve core 64 is lifted, thus cutting off the supply of compressed air to the air cylinder and opening the control valve to permit exhaust of the air from the air cylinder through the feed pipe 52 to the exhaust port 53. As the air is released the ejector slide is retracted under the action of the springs 49-52, allowing the control rod 78 and the control lever 85 to resume their normal positions, as shown in Fig. 3. As the foremost link in the chute reaches the contact portion 87 of the control lever, the cycle is repeated and another group of ten links is ejected into the carton, the action thus continuing automatically as long as the links are propelled forwardly in a continuing line in the chute.

The form of the invention illustrated in the drawings and described herein is typical and illustrative only, and it is evident that the invention is capable of embodiments in other forms, all falling within the scope of the appended claims, which are to be broadly construed.

What is claimed is:

1. In a packaging machine for packaging a group of a predetermined number of articles arranged in a row, a chute member having an en-

trance end and an exit end and adapted to convey a continuous row of articles toward said exit end as a propelling force feeds said articles into said entrance end, a reciprocatory ejector slide, projecting means for projecting said slide, retracting means for retracting said slide, control means for effecting the actuation of said projecting stroke ejector means carried by said slide engageable with the last article of a predetermined group of articles disposed forwardly of said ejector means in the retracted position of said slide, contact means engageable by the first article of said predetermined group of articles arranged to actuate said control means to effect the projection of said slide, and contact means engageable by said slide in its projected position arranged to actuate said control means to effect the termination of the projecting stroke and allow the retracting means to effect retraction of said slide.

2. In a packaging machine for packaging a group of a predetermined number of articles arranged in a row, a chute member having an entrance end and an exit end and adapted to convey a continuous row of articles toward said exit end as a propelling force feeds said articles into said entrance end, a reciprocatory ejector slide, pneumatic projecting means for projecting said slide, spring means for retracting said slide, air valve control means for effecting the actuation of said pneumatic projecting means, ejector means carried by said slide engageable with the last article of a predetermined group of articles disposed forwardly of said ejector means in the retracted position of said slide, contact means engageable by the first article of said predetermined group of articles arranged to actuate said air valve control means to effect the projection of said slide, and contact means engageable by said slide in its projected position arranged to actuate said air valve control means to permit the retraction of said slide under the action of said spring means.

3. In a packaging machine for packaging a group of a predetermined number of articles arranged in a row, a chute member having an entrance end and an exit end and adapted to convey a continuous row of articles toward said exit end as a propelling force feeds said articles into said entrance end, a reciprocatory ejector slide, pneumatic projecting means for projecting said slide, spring means for retracting said slide, air valve control means for effecting the actuation of said pneumatic projecting means, ejector means carried by said slide engageable with the last article of a predetermined group of articles disposed forwardly of said ejector means in the retracted position of said slide, a control lever having contact means engageable by the first article of said predetermined group of articles arranged to actuate said air valve control means to effect the projection of said slide, and a reciprocatory control rod having contact means engageable by said slide in its projected position arranged to actuate said air valve control means to permit the retraction of said slide under the action of said spring means.

4. In a packaging machine for packaging a group of a predetermined number of articles arranged in a row, a chute member having an entrance end and an exit end and adapted to convey a continuous row of articles toward said exit end as a propelling force feeds said articles into said entrance end, a reciprocatory ejector slide, pneumatic projecting means for projecting said slide, spring means for retracting said slide, air valve control means for effecting the actuation of

said pneumatic projecting means, ejector means carried by said slide engageable with the last article of a predetermined group of articles disposed forwardly of said ejector means in the retracted position of said slide, a control lever having contact means engageable by the first article of said predetermined group of articles arranged to actuate said air valve control means to effect the projection of said slide, an equalizer arm cooperating with said control lever and engageable by said slide in its projected position to maintain the actuated position of said control lever, and contact means engageable by said slide in its projected position arranged to actuate said air valve control means to permit the retraction of said slide under the actuation of said spring means.

5. In a packaging machine for packaging a group of a predetermined number of articles arranged in a row and wherein each of said articles is longitudinally interengaged with an adjacent article, a chute member having an entrance end and an exit end and adapted to convey a continuous row of interengaged articles toward said exit end as a propelling force feeds said articles into said entrance end, a reciprocatory ejector slide, projecting means for projecting said slide, retracting means for retracting said slide, control means for effecting the actuation of said projecting means, ejector fingers carried by said slide engageable with the last article of a predetermined group of articles disposed forwardly of said ejector fingers in the retracted position of said slide, and contact means engageable by the first article of said predetermined group of articles arranged to actuate said control means to effect the projection of said slide, whereby said last article engaged by said fingers is longitudinally disengaged from the following interengaged article and said predetermined group is ejected.

6. In a packaging machine for packaging a group of a predetermined number of articles arranged in a row and wherein each of said articles comprises an intermediate portion and two end portions adapted to be longitudinally interengaged with the intermediate portion of an adjacent article, a chute member having an entrance end and an exit end and adapted to convey a continuous row of interengaged articles toward said exit end as a propelling force feeds said articles into said entrance end, a reciprocatory ejector slide, projecting means for projecting said slide, retracting means for retracting said slide, control means for effecting the actuation of said projecting means, ejector fingers carried by said slide engageable with a rearwardly disposed interengaging portion of the last article of a predetermined group of articles disposed forwardly of said ejector fingers in the retracted position of said slide, and contact means engageable by a forwardly disposed interengaging portion of the first article of said predetermined group of articles arranged to actuate said control means to effect the projection of said slide, whereby said last article engaged by said fingers is longitudinally disengaged from the following interengaged article and said predetermined group is ejected.

7. In a packaging machine for packaging a group of a predetermined number of articles arranged in a row and wherein each of said articles comprises an intermediate portion and two end portions adapted to be longitudinally interengaged with the intermediate portion of an ad-

jacent succeeding article, a chute member having an entrance end and an exit end and adapted to convey a continuous row of interengaged articles toward said exit end as a propelling force feeds said articles into said entrance end, a reciprocatory ejector slide, projecting means for projecting said slide, retracting means for retracting said slide, control means for effecting the actuation of said projecting means, a pair of ejector means carried by said slide engageable with the two end portions of the last article of a predetermined group of articles disposed forwardly of said ejector means in the retracted position of said slide, and contact means engageable by the intermediate portion of the first article of said predetermined group of articles arranged to actuate said control means to effect the projection of said slide, whereby said last article is longitudinally disengaged from the following interengaged article and said predetermined group is ejected.

8. In a packaging machine for packaging a group of a predetermined number of articles arranged in a row and wherein each of said articles comprises an intermediate portion and two end portions adapted to be longitudinally interengaged with the intermediate portion of an adjacent succeeding article, a chute member having an entrance end and an exit end and adapted to convey a continuous row of interengaged articles toward said exit end as a propelling force feeds said articles into said entrance end, a reciprocatory ejector slide, projecting means for projecting said slide, retracting means for retracting said slide, control means for effecting the actuation of said projecting means, a pair of ejector means carried by said slide engageable with the two end portions of the last article of a predetermined group of articles disposed forwardly of said ejector means in the retracted position of said slide, pressure means within said chute member arranged to successively yieldably engage the intermediate portion of the articles of said predetermined group in opposition to said propelling force as the articles are fed through the chute, and contact means engageable by the intermediate portion of said first article of said predetermined group of articles arranged to actuate said control means to effect the projection of said slide, whereby said last article is longitudinally disengaged from the following interengaged article and said predetermined group is ejected.

9. In a packaging machine for packaging a group of a predetermined number of cartridge belt links arranged in a row and wherein each of said links comprises an intermediate loop and two end loops adapted to be longitudinally interengaged with the intermediate loop of an adja-

cent succeeding link, a chute member having an entrance end and an exit end and adapted to convey a continuous row of interengaged links toward said exit end as a propelling force feeds said links into said entrance end, a reciprocatory ejector slide, projecting means for projecting said slide, retracting means for retracting said slide, control means for effecting the actuation of said projecting means, ejector means carried by said slide engageable with said two end loops of the last link of a predetermined group of links disposed forwardly of said ejector means in the retracted position of said slide, and contact means engageable by the intermediate loop of the first link of said predetermined group of links arranged to actuate said control means to effect the projection of said slide, whereby said last link is longitudinally disengaged from the following interengaged link and said predetermined group is ejected.

10. In combination with a de-linking machine for de-linking cartridge link belts having an indexing gear for feeding said link belt, a packaging machine for packaging a group of a predetermined number of links arranged in a row and wherein each of said links is longitudinally interengaged with an adjacent link, comprising a chute member having an entrance end and an exit end and adapted to convey a continuous row of interengaged links toward said exit end as the propelling force of said indexing gear feeds said links into said entrance end, a reciprocatory ejector slide, projecting means for projecting said slide, retracting means for retracting said slide, control means for effecting the actuation of said projecting means, ejector fingers carried by said slide engageable with the last link of a predetermined group of links disposed forwardly of said ejector fingers in the retracted position of said slide, and contact means engageable by the first link of said predetermined group of links arranged to actuate said control means to effect the projection of said slide, whereby said last link engaged by said fingers is longitudinally disengaged from the following interengaged link and said predetermined group is ejected.
